US00D769514S

(12) **United States Design Patent** (10) **Patent No.:** **US D769,514 S**
(45) **Date of Patent:** **** Oct. 18, 2016**

(54) **HORTICULTURE GROW LIGHT**

- (71) Applicant: **IP Holdings, LLC**, Vancouver, WA (US)
(72) Inventor: **Chris Reynolds**, Vancouver, WA (US)
(73) Assignee: **IP Holdings, LLC**, Vancouver, WA (US)
(***) Term: **15 Years**
(21) Appl. No.: **29/546,471**
(22) Filed: **Nov. 23, 2015**

Related U.S. Application Data

- (63) Continuation of application No. 29/506,973, filed on Oct. 22, 2014, now Pat. No. Des. 747,029.

(57) **CLAIM**

The ornamental design for a horticulture grow light, as shown and described.

DESCRIPTION

FIG. 1 is a perspective view of a horticulture grow light, as viewed from below, showing my new design;

FIG. 2 is a perspective view of the light shown in FIG. 1, as viewed from above;

FIG. 3 is a left side view of the light shown in FIG. 1;
FIG. 4 is a right side view of the light shown in FIG. 1;
FIG. 5 is a front elevation view of the light shown in FIG. 1;

FIG. 6 is a rear elevation view of the light shown in FIG. 1;
FIG. 7 is a top plan view of the light shown in FIG. 1; and,
FIG. 8 is a bottom plan view of the light shown in FIG. 1.
The broken-line disclosure shown in the views is understood to represent portions of the article in which the claimed design is embodied, but which form no part of the claimed design.

1 Claim, 7 Drawing Sheets
